L. TROTZKY

UNITED STATES PATENT OFFICE.

LEON TROTZKY, OF PITTSBURG, PENNSYLVANIA.

STYLOGRAPHIC PEN.

948,832.

Specification of Letters Patent. Patented Feb. 8, 1910.

Application filed June 1, 1909. Serial No. 499,327.

To all whom it may concern:

Be it known that I, LEON TROTZKY, a subject of the Czar of Russia, residing at Pittsburgh, in the county of Allegheny and State of Pennsylvania, have invented certain new and useful Improvements in Stylographic Pens, of which the following is a specification, reference being had therein to the accompanying drawing.

10 This invention relates to stylographic pens and has for its object to provide in a manner as hereinafter set forth a simple and durable stylographic pen adapted for use with various kinds of writing fluid and 15 to furthermore provide a stylographic pen with a valve mechanism as hereinafter illustrated, which will be positive in its action and not liable to be injured through ordinary use and furthermore to provide a stylographic pen in the manner as hereinafter set forth with means whereby the writing fluid will be caused to flow freely during the use 20 of the pen.

In describing the invention in detail reference is had to the accompanying drawings wherein like reference characters denote corresponding parts throughout the several views, and in which,—

Figure 1 is an elevation of a stylographic pen in accordance with this invention, Fig. 2 is a vertical sectional view of the same, and Fig. 3 is a detail illustrating the adjusting screw and guide pin for the valve spring.

Referring to the drawings in detail 1 denotes a tube having the upper end thereof 35 interiorly screw-threaded as at 2, and its lower end threaded as at 3.

4 designates a plug adapted to screw in the upper end of the tube 1, said plug having a 40 longitudinal bore 5, the upper end of which is interiorly screw-threaded, as at 6, and terminates in an annular recess 7 formed in the upper end of the plug. The lower end of the bore 5 is constructed, to form a valve 45 seat 8, and this seat communicates with the recess 7 through the medium of a by-path 9.

10 designates a stem threaded in the upper end of the plug 4, said stem having a contracted end 11 serving functionally as a 50 valve adapted to engage the seat 8 and close the lower end of the by-path 9. The upper end of the stem is provided with a knurled cap 12 loosely fitting over the upper end of the plug 4. This cap 12 through the medium of the lower end of the stem 10 regulates the passage of air into the tube 1 and

the flow of the contents of said tube from the lower end thereof, as will hereinafter appear.

13 designates a hollow conical shaped head 60 threaded in the lower end of the tube 1. This head is provided with a longitudinal bore 14 terminating in an opening 15 at the apex of the head. In the opening 15 is soldered or otherwise secured a feed tube 16 65 having the lower end thereof contracted to a small opening 17 through which extends the writing point 18 of a rod 19. The rod 19 extends upwardly through the feed tube 16 and is connected to a valve 20 having a 70 resilient gasket 21 adapted to seat upon the upper end of the feed tube 16.

Connected to the head 13 and adapted to project in the tube 1 is a bracket 22 having its free end provided with an angularly disposed portion formed with a screw-threaded aperture through which extends a headed adjusting screw 23 provided with a depending guide pin 24 for a coil spring 25. The latter is interposed between the angular end of 80 the bracket 22 and the valve 20, and the lower end of said spring is retained in engagement with the valve by a vertical guide pin 26, carried by the valve 20 and alining with the pin 24.

The feed tube 16 in connection with the head 13 forms an annular compartment 27 in the conical end of said head, said compartment being provided for the accumulation 90 of sediment or other matter contained within the ink and detrimental to the flow of the same.

In operation, pressure upon the point 18 will shift the valve from the inner end of the feed tube thereby allowing the writing 95 fluid to pass into the tube and the point 18. Shifting of the valve 20 from the inner end of the feed tube is had against action of the spring 25, when pressure is relieved from the point 18, that is to say, when the point 18 100 is raised off of the surface being written upon, the valve 20 immediately closes the upper end of the feed tube and causes a cessation in the flow of ink from the tube 1 to the feed tube 16.

The flow of ink from the pencil can be entirely shut off by closing the by-path 9, which serves functionally as a vent, and by regulating the stem 10, the operation of the pencil can be easily controlled.

Since the cap 12 loosely fits the upper end of the plug 4, the recess 7 of the plug

prevents the upper end of the by-path or vent 9 from being closed by the cap.

The spring 25 used in connection with the pencil is made of a material not susceptible to corrosion or a chemical action by the contents of the pencil.

The pencil can be made of metal, hard rubber, or a similar strong and durable material.

Having now described my invention, what I claim as new, is:—

A stylographic pen comprising a tube constituting a reservoir, means for closing one end of said tube, said tube having its other end provided with interior threads, a hollow head comprising a cylindrical body portion and a cone-shaped outer end, said body portion provided with threads engaging with the threads of the tube whereby the head is connected to the tube, a feed tube extending through and connected to the conical end of said head, said tube extending in said body portion and projecting from said conical

end, a rod arranged in the feed tube and projecting from the outer end of the feed tube and constituting a writing point, said rod projecting in said reservoir, a valvular means connected to said rod intermediate its ends and engaging the inner end of said feed tube for closing it, an inverted L-shaped bracket connected to the inner end of said head, a coiled spring interposed between said bracket and said valve and constituting a means for maintaining the valve against the feed tube for closing it, said valve actuated from its seat when pressure is applied to said rod, and means carried by the bracket for adjusting the tension of said spring.

In testimony whereof I affix my signature in the presence of two witnesses.

LEON TROTZKY.
